JOSEPH E. LARKINS, OF LOUISVILLE, KENTUCKY, ASSIGNOR TO PLYWOOD PRODUCTS COMPANY, OF LOUISVILLE, KENTUCKY, A CORPORATION OF KENTUCKY

FLOORING CONSTRUCTION

Application filed November 24, 1930. Serial No. 497,864.

The invention relates to flooring construction and has for its objects to provide material improvements in reinforcing the aligned floor blocks or boards against warping and expansion, as well as other distortion commonly encountered which otherwise results in unevenness and imperfection in the flooring.

An important object of the invention is to provide reinforcement for the flooring which is designed to prevent warping and expansion and consequent unevenness in the flooring along the joint or meeting lines of the floor parts or blocks. The flooring blocks or parts are usually constructed with a tongue and groove connection so that the parts may be nested closely together and maintained in relation to one another. Due to variations in temperature and atmospheric influences, as well as other causes, the boards tend to shrink or expand and become separated from one another in horizontal as well as vertical planes. Such warping or distortion is usually manifest at the meeting lines of the boards, there being least resistance at these points due to the tongue and groove construction. The present invention adequately reinforces the tongue and groove connection between the boards, as well as the remaining portions of the floor elements so as to effectually resist any atmospheric or other influences having a tendency to expand, shrink or warp the flooring.

The invention is equally applicable and advantageous when used in solid plank floors, and integral as well as composite blocks for use in laying parquet or mosaic flooring. With such objects in view, as well as other advantages which may be incident to the use of the improvements, the invention consists in the parts and combinations thereof herein-after set forth and claimed, with the understanding that the several necessary elements constituting the same may be varied in proportion and arrangement without departing from the nature and scope of the invention.

In order to make the invention more clearly understood there are shown in the accompanying drawings means for carrying the same into practical effect, without limiting

the improvements, in their useful applications, to the particular constructions which, for the purpose of explanation, have been made the subject of illustration.

In the said drawings:

Fig. 1 is a plan view of a section of parquet flooring constructed in accordance with the invention.

Fig. 2 is a similar view looking at the bottom or lower side of the laid flooring blocks.

Fig. 3 is a vertical section on line 3—3 of Fig. 1.

Fig. 4 is a similar view on line 4—4 of Fig. 2.

Fig. 5 is an enlarged bottom plan view of one of the flooring blocks illustrated in the preceding figures.

Fig. 6 is an edge view of the same looking from the bottom as viewed in Fig. 5, it being understood that the block is shown in inverted position to better illustrate the invention.

Fig. 7 is a similar view looking from the upper side of Fig. 5.

Fig. 8 is a section on line 8—8 of Fig. 5.

Fig. 9 is a similar view on line 9—9 of Fig. 5.

Fig. 10 is a perspective view of a modified form of block constructed in accordance with the invention and looking at the bottom side thereof.

Fig. 11 is a section on line 11—11 of Fig. 10.

Fig. 12 is a similar view on line 12—12 of Fig. 10.

Fig. 13 is a perspective view of a section of solid plank flooring constructed in accordance with the invention and looking at the bottom side thereof to more clearly illustrate the improvements.

Fig. 14 is an enlarged detail plan view of one of the planks illustrated in Fig. 13.

Fig. 15 is a still further enlarged sectional view on line 15—15 of Fig. 14.

Referring to the drawings, 1 indicates the flooring blocks which are constructed of various kinds of wood, preferably hard woods such as white oak or walnut, which are well known and suited for the purpose. Each block is or may be formed of one solid piece of lumber and is provided on two adjacent

95

100

105

edges with an integrally formed tongue 2 and on the remaining two adjacent edges with a groove 3. The tongue and groove construction is to permit the flooring blocks 5 to be closely assembled and interlocked with one another to provide a smooth unitary flooring.

Each flooring block 1 is further provided, preferably on the under side thereof, with 10 one or more recesses 4 which extend entirely across the block from one vertical edge to the other. In the preferred form of the invention, and as illustrated, two recesses 4 are provided in each block, said recesses being 15 preferably of dove-tail configuration. The described recesses 4 extend in depth from the lower side of the block to a point substantially midway of its vertical dimension or thickness, which is substantially midway of 20 the thickness of the tongue member 2 and groove 3 respectively located at the opposite extremities of the said recesses. The grooves are preferably substantially parallel to one another and are disposed adjacent the opposite 25 site edges of the block. The recesses 4 are further preferably formed in the block across the grain of the latter or substantially at right angles thereto, as illustrated in Figs. 2 and 5.

30 The grooves are designed to receive therein correspondingly shaped closely fitting splines or keys 5 preferably of hard wood, or the splines may be formed of a wood corresponding to the material of which the block is constructed. The splines 5 are preferably glued 35 in position to guard against endwise displacement and are otherwise locked in position by the dovetail configuration of the recess 4. The spline members 5 are preferably of a 40 thickness or depth somewhat less than the recess 4 (Figs. 6 and 8) to insure against any resulting unevenness in laying or applying the flooring.

45 As best seen in Figs. 2 and 5 the grain of the splines 5 lies substantially at right angles to that of the blocks 1, thereby aiding materially in strengthening the block and preventing any tendency of the latter to warp, shrink or expand due to atmospheric or other 50 influences.

55 Referring to Figs. 5 to 9 inclusive, it will be seen that the spline 5 projects into and constitutes a part of the tongue 2 at one vertical edge of the block, as indicated at 6. At its opposite end each spline 5 extends 60 into and constitutes a part of the groove 3 as indicated at 7. The respective tongues 2 and grooves 3 are preferably formed after the splines have been inserted and secured in place, so that the opposite ends of the spline will be shaped and cut away to conform to the configuration of the tongue 2 and groove 3 respectively of the block. By this configuration 65 it will be evident that the tongue and grooves as well as the laid flooring blocks are

strongly reinforced by the splines against any warping or shrinking tendencies, not only within the area of the blocks proper, but also at their meeting junctures. It is at the meeting or uniting lines of adjacent 70 blocks that the warping or expansion is most likely to occur and is manifest by a slight depression or elevation of one block relative to the other, as frequently results from the usual non-reinforced tongue and groove construction. This area of the block, by reason of the reduced dimensions, offers least resistance to such warping stresses. By extending the splines 5 horizontally and vertically 75 into the tongue and groove respectively of each block to constitute integral parts of the same, and shaping the ends of the splines to conform to the configuration of said tongue and groove, materially aids in strengthening 80 these parts to effectually resist any warping or expanding movements of the flooring along the meeting edges or lines of the adjacent blocks. The body portion of the spline adequately strengthens and reinforces the 85 remaining area of the block as will be obvious. 90

95 As best seen in Fig. 2 the construction of the tongue and groove elements 2 and 3 of the blocks permits the same to be laid alternately, that is with the grain of each block running at substantially right angles to the grain of the adjacent block. Similarly the disposition and grain of the splines 5 of the laid blocks are at right angles to one another in adjoining blocks, thereby serving 100 to materially and most effectually reinforce the tongue and groove connections at the meeting or interlocked edges of the blocks at all points of the flooring.

105 When the blocks are constructed in accordance with the invention and a flooring laid as above described, the latter will be strongly reinforced to resist atmospheric changes which would otherwise result in warping, as well as any tendency of the blocks to expand or shrink. 110

115 Referring to Figs. 10 to 12 inclusive, the flooring block is illustrated as consisting of a plurality of cabinet jointed pieces or boards 8 which are fabricated to form a unitary block. Such fabricated block 1a is provided, as in the instance of the integral block, with tongues 2a on adjacent edges and corresponding grooves 3a along the remaining adjacent edges. The splines 5a are inserted and glued 120 within the recess 4a extending for the full width of the fabricated block. As in the instance of the unitary block the splines 5a extend into and form a part of the groove at one side or edge of the block as indicated at 9 and in a similar manner extend into and are shaped to form a part of the tongue 2a at the opposite side of the block, as indicated at 10. In this manner parquet flooring blocks may be constructed of a plurality of 125 parts or members 8 which are cabinet jointed 130

and securely locked together by the splines 5a which latter contribute to the secure reinforcement of the block against warping and atmospheric changes in the same manner and for the reasons above described. As in the instance of the integrally formed block, the grain of the fabricated blocks 10 is of preference disposed at right angles to the grain of the keys or splines 5a. This is to bring about added reinforcement for the reasons hereinbefore pointed out.

Referring to Figs. 13 to 15, there is illustrated a section of solid plank flooring which may be constructed of the usual solid board planks 1b of various or random lengths and widths, and which have the usual tongue and groove connection 2b, 3b respectively, therebetween. It is common with such type of floors to employ planks of 10 to 12 feet long, and in the instance of the present invention each plank is provided along its length with a plurality of splines 5b which may be spaced approximately ten inches apart along the longitudinal dimension of the plank; said splines being disposed in staggered relation as illustrated, if desired. The splines 5b are individual to the respective planks 1b, and as best seen in Figs. 15, extend vertically for substantially half the thickness of the plank. As in the instance of the described blocks, the splines are inserted in dovetail recesses 4b in the under surface of the planks and extend transversely thereof. The said splines are shaped to constitute a part of the tongue as at 11 and are further formed to constitute a part of the groove as at 12 on the opposite side of the plank. It is further preferable to have the grain of the splines 5b running at right angles to the grain of the planks for best results as in the former described embodiments of the invention. It will therefore be seen that the aligned planks are effectually reinforced against warping and expansion by virtue of the nature and extent of the spline 5b, particularly at their separation lines so that smooth and even flooring of a permanent nature is obtained.

A smooth, uniform and permanent flooring is obtained by the invention, and said flooring is amply reinforced at the points of least resistance to said outside influences and stresses, namely at the juncture or interlocked meeting lines of the blocks.

What is claimed is:

1. A flooring element having a tongue and groove respectively on opposite edges thereof, a recess formed in one surface of said element and extending from said tongue to said groove, and a spline secured in said recess, the outer surface of said spline being substantially coincident with the outer surface of said flooring element, and the inner part of said spline at one end forming a part of said tongue, and at its other end forming

a part of the inner and bottom walls of said groove.

2. A fabricated flooring block having a tongue and groove respectively on opposite sides thereof and composed of a plurality of boards closely abutting one another and secured together in side by side relation, a recess formed in one surface of said block and extending from edge to edge thereof transversely of said boards, and a spline secured in said recess, the outer surface of said spline being substantially coincident with the corresponding surface of said block and the inner part of said spline extending vertically and horizontally into and constituting at one end a part of the tongue and at its other end forming a part of the inner and bottom walls of the groove of said block.

3. In a flooring, the combination of a plurality of flooring blocks interlocked together by tongue and groove connections, each block having dovetail recesses in their under surfaces and a spline member embedded in and conforming to each of said recesses and extending continuously from edge to edge of the block, the narrow surface of said splines extending substantially to the under surface of the block and the wide part of said splines extending into and constituting at one end a part of said tongue, and at its other end forming a part of the inner and bottom walls of said groove, whereby each of said interlocked flooring blocks is reinforced against warping strains from edge to edge thereof.

In testimony whereof I affix my signature.
JOSEPH E. LARKINS.
